MULTICOLOR SHUTTLE CHANGER LOOM

Richard G. Turner, Worcester, Mass., assignor to
Crompton & Knowles Loom Works, Worcester,
Mass., a corporation of Massachusetts

Application October 8, 1934, Serial No. 747,358

11 Claims. (Cl. 139—232)

This is a continuation in part of my application Serial Number 585,564.

This invention relates to improvements in multicolor shuttle changing looms more particularly of the type wherein the replenishment of the various kinds of shuttles take place at the same side of the loom and it is the general object of the invention to provide improved means for advancing a selected shuttle from any of the reserve stacks to changing position.

In the type of loom to which my invention more particularly relates there are stacks of reserve shuttles, and shifting shuttle boxes which alter their position in order to receive and discharge the spent shuttle and at the same time to receive a full shuttle from the magazine. Where the boxes and magazine have independent controls, one may operate without the other and cause faulty operation. It is an important object of my present invention to actuate the rising boxes and the reserve shuttle advancing mechanism of the magazine through a common member, so that both of these mechanisms will be required to operate not only on the same beat of the loom but in a definite time relation. The means for accomplishing this result may include a set of hooks or the like to be called into action one at a time by a normally idle actuator controlled by the weft detector mechanism. Relative motion between the hooks and actuator is caused by a color selector movable in timed relation with the weaving shuttles.

While the actual coordinating mechanism is mechanical in its operation, yet I have shown herein an electro-magnetic control and it is a further object of my invention to provide devices which permit the momentary actuation of the magnetic circuit to set the shuttle advancing mechanism, a yielding lock or the like being provided which will act to hold an actuator and the shuttle advancers in operative position even though the controller circuit should become broken for any reason. The lock as shown herein is of the type which serves to unlock itself on the return or non-working stroke of the actuator.

With these and other objects in view which will appear as the description proceeds, my invention resides in the combination and arrangement of parts hereinafter described and set forth in the claims.

The magazine control mechanism includes hooks movable to be operatively relatable one at a time to an actuator called into action by weft detector mechanism. It is a further object of my invention to provide an improved form of

actuator capable of assuming different settings so that the time of beginning and ending the magazine operations may be varied. In this connection a stop collar may be used on one of the shuttle releasing devices to prevent excess motion which would result in moving the incoming shuttle too far.

The previously mentioned hooks are subjected to a constant back and forth motion under control of the pattern mechanism. In order to prevent breakage of the hooks and their connectors I propose to use yielding connections which will absorb the shock caused by the color slide.

In the accompanying drawings, wherein a convenient embodiment of my invention is set forth,

Fig. 1 is a side elevation of the lower part of a loom having my invention applied thereto,

Fig. 2 is a view of the upper part of the loom on the same side, certain parts being in section,

Fig. 3 is a plan view taken in the direction of arrow 3, Fig. 1,

Fig. 4 is a horizontal section on line 4—4 of Fig. 1,

Fig. 5 is a diagrammatic view of the circuits and certain parts of the loom structure, showing both sides of the loom,

Fig. 6 is a detailed vertical section through a part of Fig. 2, showing the devices for advancing a shuttle from either stack to transfer position, and

Figs. 7, 8 and 9 are diagrammatic views showing the various operations of the lock, when viewed in the direction of arrow 7, Fig. 3.

Referring to the drawings, particularly to Fig. 5, I have shown the lay L provided with upper and lower drop boxes 10 and 11, respectively, at the left hand side to accommodate shuttles having two different kinds of weft. The pattern mechanism P is composed of a lever 12 having a run 13 positioned to engage successively the pattern chain balls 14. When a low ball appears under the lever the latter will fall as is usual, but when a high ball rolls under the lever, the latter is raised to lift rod 15. A rocking lever 16 pivoted near the bottom of rod 15 at A is connected to the rod so as to rock with lever 12, and two switches 17 and 18 are opened and closed by the pattern mechanism acting through the lever 16.

On the opposite side of the loom is the magazine M which in in the present instance is provided with a dividing plate 20 separating the magazine into front and back compartments 21 and 22, respectively. A release lever 23 has a foot 24 projecting into the front guideway to support the front reserve shuttles, while a plunger 25 is located be-

hind the rear guideway. A support 27 is provided for the rear reserve shuttles the bottom one of which rests on the support. As shown herein a movable platform 28 is under the front 5 stack and in front of the lowest shuttle of the rear stack.

The lever 23 may have an arm 29, see Fig. 2, connected to a wire 30 extending through a coil wire sheath 31 and passing downwardly to be 10 connected to a rod 32 as shown in Fig. 1. The plunger 25 has a rearwardly extending stem 33 having a pin and slot connection with a bell crank lever 34 movable about fixed pivot 35 and deriving an actuating force from a rod 36 attached to said 15 lever 34.

The right hand side of the lay shown in Fig. 5 is provided with an upper shuttle box 40 normally in active position, and a lower box 41 normally inactive. These boxes are supported by a rod 42, 20 the lower end of which is operatively connected to a lever 43 by means of an adjustable stud 44 on the lever, and a yielding connection comprising two hinged parts 45 and 46 yieldingly held to the stud. The box rod may be pivoted to link 46, 25 all as usual.

The bottom shaft 50 of the loom has a groove cam 51 which receives a roll 52 on a lever 53 given regular motions by the cam. The forward end of lever 53 has pivoted thereto a latch 54 normally held in inoperative position by means of a spring 55 so that as the lever 53 rocks periodically the latch will normally clear a lifting ledge 56 formed on the lever 43. A solenoid 57 carried by the lever 53 is effective when energized to move the 30 latch to the position indicated in Fig. 7 under the ledge 56, so that upward movement of the forward end of the lever 53 will raise the lever 43 to lift box rod 42.

The matter thus far described forms no part of 40 my present invention. The magazine as shown in Fig. 2 and a portion of the mechanism shown in Fig. 1 may be as set forth in a shuttle changing loom heretofore proposed by me and shown in application Serial No. 460,746. For the purposes 45 of the present description it is sufficient to state that the operation of the magazine requires the downward movement of one or the other of the rods 32 or 36, depending upon which shuttle is active. The platform 28 will receive a reserve 50 shuttle and the shuttle changing boxes 40 and 41 will rise so that the top box will receive the shuttle on the platform and the spent shuttle coming from the opposite side of the loom will enter the lower box 41. The platform may be 55 moved rearwardly to permit the shuttle on it to fall into the top box. Thereafter, downward movement of the shuttle changing boxes to the normal running position will be accompanied by an ejection of the spent shuttle from the lower 60 box, and placing of the new shuttle into action by the top box.

The loom may be operated with call boxes by 65 means of connections shown in Fig. 5, either of the shuttles remaining active as long as desired, with assurance that the replacement of an exhausted idle shuttle will not take place until it returns to action. In this connection I may provide the upper box 10 with contacts 58 and 59, and the lower box with contacts 60 and 61. Contacts 59 and 61 are grounded by wire 62, while wire 63 connects contact 58 with point 66 of switch 17, and wire 64 connects contact 60 with point 67 of switch 18. Switch points 75 and 76 of switches 17 and 18, respectively, are connected 75 by a wire 68 to the solenoid 57, and the latter is

connected by wire 69 to a transformer 70. The solenoid may be grounded by wire 71, and the core of the solenoid may be mechanically connected as at 72 to the latch 54 to oppose spring 55.

By means of these connections it will be necessary not only to have a circuit closed through one or the other of the shuttles on the pattern mechanism side of the loom, but it will also be necessary to have the proper switch 17 or 18 closed, depending upon which shuttle is next to be active, 10 before the solenoid 57 can be actuated. In this way a depleted shuttle may remain idle on the pattern mechanism side of the loom without bringing about operation of the magazine.

My present invention includes means for co-ordinating the movements of the boxes and shuttle advancers 24 and 25, and also improved means for actuating the rods 32 and 36, together with a lock effective to insure coaction between the actuator and the box. In carrying my invention into effect I provide the lower ends of rods 32 and 36 with rearwardly and forwardly extending hooks 80, and 81, respectively. The normally stationary lever 43 is provided with a rear extension 82 having an arcuate substantially vertical slot 83 in which is adjustably held an actuator 77 held at the desired vertical position by nut 78. The actuator stud extends over the hooks and is normally at rest but is movable downwardly along a determined path when lever 30 43 is oscillated.

A sliding block or positioner 84 is mounted in a guide stand 85 secured to the loomside as shown in Fig. 3, and the hooks 80 and 81 pass through slots 86 and 87, respectively, in said slide. A 35 tension spring 88 interposed between the slide and a fixed part of the stand 85 tends normally to move said slide forwardly, or in such position as will place the hook 81 normally under the actuator 77. A flexible connection 89 as shown in 40 Fig. 5 is connected to a reversing lever 90, and a second flexible connection 91 extends from said lever around a sheave 92 to a finger 93 secured to the rod 15. The spring 88 serves to hold the lever 12 down against the pattern chain and the latter moves the slide against the action of the 45 spring.

When the lever 12 is raised the parts will be in the position shown in Fig. 1 with the hook 80 under the actuator 77, and when the pattern 50 chain permits lowering of the lever 12 the spring 88 will move the slide 84 to the left as viewed in Fig. 1 to place hook 81 under the actuator 77. By the mechanism just described the pattern 55 mechanism is effective to place one or the other of the hooks 80 or 81 in operative position with respect to the actuator 77 to cause depression of one or the other of the rods 32 or 36 to advance the shuttles as already described.

I have found it desirable to interpose a shock 60 absorbing connection between the rods 32 and 36 and their respective hooks in order to prevent breakage of the hook and rod connections as the slide 84 reciprocates. Accordingly, each rod has a spring 73 located between a stop collar 74 and the top of the associated hook. Check nuts 79 65 position the hooks vertically and receive the downward thrust of the spring on the hooks. By the connection described the hooks are yieldable transversely of the axis of their pull rods to relieve any strains which might result from movement of the slide 84.

Where the loom is run at high speed there is the possibility that vibration may shake the electric contacts so that the current flowing through 75

the solenoid will be interrupted with consequent deenergization of the solenoid field. Under these conditions the latch will return to its inoperative position if the actuator lever 53 has not started on its working stroke, and to prevent such a condition I use a lock for the latch which will act to hold the latter in its operative position until the working stroke of the lever 53 will bring about engagement between the latch and the lifting ledge 56.

The lock is shown in Fig. 7, where it will be seen that the normally stationary lever 43 has a flat horizontal spring 100 which may extend over the ledge 56 and has a hook end 101 bent up and back toward the lever carried support 102 of the spring. The latch has an upwardly extending relatively rigid hook 103 having an inclined surface 104 adapted to coact with the hook 101.

When the solenoid acts through the connection 72 the latch will move to the position shown in Fig. 7, causing the rigid end 104 to pass over and to the right of the yielding spring hook 101. Hook 101 will temporarily move to the dotted line position shown in Fig. 7. Thereafter, one of two conditions can exist, namely, either the solenoid will remain energized, or a break will develop in the circuit and the solenoid will release the latch.

If the first condition exists, the lever 53 will raise the latch on its working stroke until the latter engages the overhang 56, thereby lifting the actuator. During this operation the hook 104 is held by the solenoid out of engagement with the spring hook 101, although starting its up motion from a position below the top of the spring hook. The rigid hook rises with a relatively quick motion to a position above the spring hook before the latch engages the overhang 56, so that on the following slower down motion of lever 53 on its non-working stroke, the spring 55 will have time to move hook 104, clear the hook 101, thus permitting the parts to return to normal position.

If the other condition exists, that is, if the solenoid becomes deenergized before the latch and overhang interengage each other, the rigid hook 104 will be moved by spring 55 against holding hook 101 to the position shown in Fig. 8. The left inclined surface 105 of hook 104 will lie against the spring hook 101 to hold the latch under the overhang 56, although farther from the lever 43 than with the first condition shown in Fig. 7.

During the beginning of the working stroke of lever 53 under this second condition the rigid latch, released by the solenoid and stressed by spring 55, will maintain engagement with the spring hook 101, bending the latter upwardly from the dotted to the full line position of Fig. 8 until the latch engages the overhang and starts to be cammed toward lever 43 by the inclined under surface 106 of the ledge 56. At about this time, with the parts in the position shown in full lines in Fig. 9, hook 104 moves to the right and separates from hook 101, after which the spring hook 101 returns to the dotted line normal position shown in Fig. 9. On the following return or non-working stroke of the latch, the rigid hook will pass over and to the left of the spring hook, to restore the parts to normal position, as in the previous condition.

Under either condition one or the other of the hooks will be depressed to advance the selected reserve shuttle toward box 40. In order that

plunger 25 may not move its shuttle too far forwardly, I provide a stop collar 110 on stem 33 and this collar engages a fixed part of the magazine for the purpose mentioned.

By the mechanism described in connection with Figs. 8 and 9, assurance is given that a single energization of the solenoid will result in depression of the proper rod 32 or 36, depending upon which shuttle is exhausted.

From the foregoing it will be seen that I have provided a common actuator for the box rod 42 and the shuttle advancers. In the present instance this common actuator is the lever 43 which acts to advance a shuttle toward changing position only at such times as the shifting boxes at the magazine end of the loom are rising to effect the exchange of shuttles. In this way the two devices which must coact to complete a change of shuttles are required to move together, movement of each device being dependent upon movement of the other device. It will further be seen that the locking mechanism of which hooks 101 and 104 are parts operates independently of the solenoid to insure movement of the actuator 77. Furthermore, it will be seen that the pattern mechanism operates by means of mechanical connections to select which of the shuttle advancers shall be positioned for transfer, while at the same time this same mechanism controls one of the two breaks of the solenoid circuit, acting to close a particular contact just prior to the return to action of its corresponding idle shuttle. Also, the actuator stud 77 is adjustable on its supporting lever and the hooks are connected to their rods by shock absorbing connections.

Having thus described my invention it will be seen that changes and modifications may be made therein by those skilled in the art without departing from the spirit and scope of the invention and I do not wish to be limited to the details herein disclosed, but what I claim is:

1. In a multicolor shuttle changing loom having a plurality of groups of reserve shuttles, a plurality of shuttle advancers, one for each group of shuttles, to place a selected shuttle in transfer position, shifting shuttle box mechanism movable to a position to receive a shuttle in transfer position, and a unitary actuator to be operatively related to the box mechanism and any selected advancer to cause coordinated movements of the advancer and box mechanism simultaneously.

2. In a multicolor shuttle changing loom having a plurality of groups of reserve shuttles, a plurality of shuttle advancers, one for each group of shuttles, to place a selected shuttle in transfer position, shifting shuttle box mechanism movable to a position to receive a shuttle in transfer position, a positioner to place the advancers, one at a time, in transfer position, and an actuator to move the advancer in transfer position and also the shuttle box mechanism simultaneously.

3. In a multicolor shuttle changing loom having a plurality of groups of reserve shuttles, a plurality of shuttle advancers, one for each group of shuttles, to place a selected shuttle in transfer position, shifting shuttle box mechanism movable to a position to receive a shuttle in transfer position, a positioner to place the advancers, one at a time, in transfer position, and a single actuator to be in position to transmit simultaneously operating forces to the box mechanism and also the advancer in transfer position.

4. In a multicolor shuttle changing loom operating with a plurality of shuttles and having a plurality of groups of reserve shuttles, an advancer for each group to move a shuttle from the corresponding group to a transfer position, a device to move toward said transfer position to take the shuttle in such a position, a lever to be operatively related to the device and one only of said advancers, and means effective upon exhaustion of weft in the running shuttle to operatively relate the lever to the device and the advancer simultaneously corresponding to the exhausted shuttle.

5. In a multicolor shuttle changing loom operating with a plurality of shuttles and having a plurality of groups of reserve shuttles, an advancer for each group to move a shuttle from the corresponding group to transfer position, a device to move toward said transfer position to take a shuttle in such a position, a normally stationary lever to be operatively related to the device and the advancer corresponding to the depleted shuttle, and means to move said lever to cause simultaneously coordinating movements of the device and advancer corresponding to the depleted shuttle.

6. In a multicolor shuttle changing loom operating with a plurality of shuttles and having a plurality of groups of reserve shuttles, an advancer for each group to move a shuttle from the corresponding group to a transfer position, a device to move toward said transfer position to take a shuttle in such position, and a single lever effective to move the device toward transfer position and simultaneously actuate the advancer of the group corresponding to the depleted shuttle, said lever thereby being effective to advance a shuttle and the device toward the transfer position.

40 7. In a multicolor shuttle changing loom operating with a plurality of shuttles and having a plurality of groups of reserve shuttles, an advancer for each group to move a shuttle from the corresponding group to transfer position, a device to move toward said transfer position to take the shuttle in such position, a regularly moving member, an element to be operatively related to the device and the advancer corresponding to the active shuttle, and means operative upon indication of weft exhaustion in the active shuttle to relate the member to the element to cause

movement of the latter which is effective to move the device and one of the advancers simultaneously.

8. In a multicolor shuttle changing loom operating with a plurality of shuttles and having a plurality of groups of reserve shuttles, a lay, an advancer for each group to engage a shuttle from the corresponding group to transfer position, a device to move toward said transfer position to take the shuttle in transfer position, a unitary actuator mounted independent of the lay for the device and the advancers, and a positioner movable in timed relation with the active shuttle to position but one of the advancers at a time operatively with respect to the unitary actuator. 15

9. In a multicolor weft replenishing loom having a plurality of groups of reserve shuttles, a lay, an advancer to engage each group, movement of any advancer being accompanied by movement of a shuttle from the corresponding group toward a common transfer position, a movable advancer actuator constituting a single unitary device movable independent of the lay, and means to move all of said advancers and to relate but one of them at a time to the unitary actuator device.

10. In a multicolor weft replenishing loom having a plurality of groups of reserve shuttles, an advancer for each group, movement of any advancer being accompanied by movement of a shuttle from the corresponding group toward a common transfer position, a regularly moving member, an actuator for the advancers, a latch movable to position to transmit force from the member to the actuator to move the latter at 35 weft exhaustion, means to lock the latch in force transmitting position, and means to relate the actuator to one only of the advancers at a time.

11. In a multicolor weft replenishing loom having a plurality of groups of reserve shuttles, an advancer for each group, movement of any advancer being accompanied by movement of a shuttle from the corresponding group toward a common transfer position, a regularly moving member, an actuator for the advancers, means 45 movable at indication of weft exhaustion to a position to operatively relate the member and actuator, and a lock for the means to hold the latter in position to transmit force from the member to the actuator. 50

RICHARD G. TURNER.
